UNITED STATES PATENT OFFICE.

ARTHUR MORGAN, OF WILKES-BARRE, PENNSYLVANIA.

RIBBON-HOLDER.

957,700.

Specification of Letters Patent. Patented May 10, 1910.

Application filed September 21, 1909. Serial No. 518,755.

To all whom it may concern:

Be it known that I, ARTHUR MORGAN, a citizen of the United States, residing at Wilkes-Barre, in the county of Luzerne and State of Pennsylvania, have invented new and useful Improvements in Ribbon-Holders, of which the following is a specification.

The invention relates to an improvement in ribbon holders, being more particularly directed to a device designed for removable connection to a roll of ribbon and adapted when in position to fix the ribbon with relation to the roll at any desired point in the length of the ribbon.

The main object of the present invention is the provision of a ribbon holder including engaging elements designed to coöperate with opposing edges of the roll, the elements being connected by a holding member designed to extend transversely of and overlie the ribbon, whereby to fix the ribbon with relation to the roll at any desired point in its length without perforating or in any way marring the ribbon or the material on which it is wound.

The invention in its preferred details of construction will be described in the following specification, reference being had particularly to the accompanying drawings, in which:—

Figure 1 is a plan of a ribbon roll, showing the improved holder applied thereto. Fig. 2 is a vertical section, partly in elevation, on the line 2—2 of Fig. 1. Fig. 3 is a perspective of one of the engaging elements. Fig. 4 is a perspective of the other engaging element.

Referring particularly to the accompanying drawings, it will be noted that the improved holder is designed for use in connection with the ordinary ribbon roll in which the desired length of ribbon 1 and underlying strip of paper 2 or the like is wound about a suitable box 3.

Ordinarily the end of the ribbon is secured in position by pins or other fastenings, and such method of fixing the ribbon to the roll is also usually employed when a portion of the ribbon is wound from the roll for display or like purposes. This method of securing the ribbon is objectionable as it perforates the same, interfering with its appearance and sale as a perfect article.

The object of the present invention is to provide a holder which possesses all the ad-

vantages of the usual pinning or fastening without in any way marring the material.

The improved holder comprises engaging elements 4 and 5, the former preferably constituting an elongated triangular member 6 constructed of a single length of wire and having a length somewhat less than the width of the roll with which it is to co-operate. At the base end of the member 6 the cross bar is provided with a hinge connecting section 7 preferably constructed of a single strip centrally and loosely coiled about the cross bar with its ends beyond said coil portion arranged in contact and formed with registering openings providing an eye 8. The other engaging member 5 is also constructed of a single length of material preferably wire centrally bent to form an eye 9 and projected therefrom to provide divergent arms 10, the terminals of which are bent downwardly and on converged lines to form a hook 11. The respective engaging elements are connected by an elastic strip 12, preferably in the form of a rubber band, looped at the ends in the eyes 8 and 9.

In use, one of the engaging elements, as 4, is inserted for its full length between superimposed layers of the roll from one side thereof, while the remaining engaging element is carried across the surface of the roll and its hook end 11 engaged beneath a suitable number of layers of the opposing edge of the roll. By this means the holding strip 12 is stretched tightly across the ribbon with the effect to fix the ribbon at such line with relation to the roll, and prevent unwinding of the ribbon beyond such line.

The holder may be secured to permit the free projection of any desired length of ribbon, so that a portion of the ribbon may be left free for display purposes, or the extreme end of the ribbon may be fixed to the roll as is desirable in storage.

The salient feature of the present invention resides in the opposing hook members to engage the opposite edges of the roll and an intermediate holding member to overlie and bear against the ribbon to secure the same in fixed relation to the roll on a line transverse thereof. In this connection it is to be understood that while preferring the construction shown and described, I do not desire to limit myself thereto, as the holding member may be constructed of an inflexible length of material connected to the engaging members by short lengths of ex-

pansible material, or the engaging members, may be otherwise formed or constructed. Therefore, I contemplate as within the spirit of the present invention all such changes and 5 variations of the present construction as may fall within the scope of the appended claim.

I claim:—

10 A ribbon holder including a triangular engaging member, a section movably connected with said member, a hook member in-

cluding a hook and a bearing portion, and an extensible connector joining the bearing portion of the hook member and the section movably connected to the engaging member. 15

In testimony whereof I affix my signature in presence of two witnesses.

ARTHUR MORGAN.
